DESIGN FOR A COMBINED CHAIR AND VIBRATOR

John Werner, Chicago, and Albert H. Zeigler, Kenilworth, Ill., assignors to Aciform Corporation, Chicago, Ill., a corporation of Illinois

Application November 12, 1947, Serial No. 142,474

Term of patent 7 years

(Cl. D15—1)

To all whom it may concern:

Be it known that we, John Werner and Albert H. Zeigler, both citizens of the United States of America, and residents of Chicago and Kenilworth in the county of Cook and State of Illinois respectively, have invented a new, original, and ornamental Design for a Combined Chair and Vibrator, of which the following is a specification, reference being had to the accompanying drawing, forming part thereof.

Figure 1 is a perspective view of a combined chair and vibrator, showing our new design.

Fig. 2 is a top plan view thereof.

Fig. 3 is a rear elevational view thereof.

Fig. 4 is a side view thereof with a portion of the upper end of the back shown broken away for convenience of illustration.

In Figs. 1 and 2 the middle panel of the back thereof is not shaded, to show the contrasting appearance of the back portion.

We claim:

The ornamental design for a combined chair and vibrator, as shown and described.

JOHN WERNER.

ALBERT H. ZEIGLER.
